[57] CLAIM

The ornamental design for a housing for a high-pressure cleaning apparatus and housing therefor, as shown and described.

DESCRIPTION

FIG. 1 is a perspective view of a housing for a high pressure cleaning apparatus showing my new design;

FIG. 2 is a right side elevational view thereof;

FIG. 3 is a top plan view thereof;

FIG. 4 is a front elevational view thereof;

FIG. 5 is a rear elevational view thereof;

FIG. 6 is a bottom plan view thereof; and,

FIG. 7 is a left side elevational view thereof.

The electric cord shown broken away in FIGS. 1-3 and 5-7 is understood to represent indeterminate length.
